UNITED STATES PATENT OFFICE.

ALEXANDER RISPEL, OF CHICAGO, ILLINOIS, ASSIGNOR OF ONE-HALF TO LOUIS H. LIEDTKE, OF CHICAGO, ILLINOIS.

DOOR CHECK AND HOLDER.

1,115,574.

Specification of Letters Patent.

Patented Nov. 3, 1914.

Application filed December 5, 1913. Serial No. 804,922.

To all whom it may concern:

Be it known that I, ALEXANDER RISPEL, a citizen of the United States, residing at Chicago, in the county of Cook and State of Illinois, have invented a new and useful 5 Door Check and Holder, of which the following is a specification.

The present invention relates to improvements in door checks and holders, the present invention being an improvement upon the door check and holder set forth in my Patent No. 1,053,222 granted February 18, 10 1913, one object of the present invention being the provision of a lug carrying means for properly gripping the upper end of the casing to position the lug properly to be abutted by the resilient abutment of the door connecting arm and to hold and prevent the accidental closing of the door after once positioned.

With the foregoing and other objects in view which will appear as the description proceeds, the invention resides in the combination and arrangement of parts and in the 25 details of construction hereinafter described and claimed, it being understood that changes in the precise embodiment of the invention herein disclosed can be made within the scope of what is claimed without departing from the spirit of the invention.

In the drawings—Figure 1 is a front elevation of the complete door check and holder with the jointed arm removed. Fig. 2 is a top plan view of the complete door 35 check and holder. Fig. 3 is a section taken on line 3—3 of Fig. 2. Fig. 4 is a section taken on line 4—4 of Fig. 3. Fig. 5 is a section taken on line 5—5 of Fig. 3. Figs. 6 and 7 are detail views of a portion of one 40 of the jointed arms carrying the anti-frictional abutment for engaging the cover lock. Figs. 8 and 9 are detail fragmentary perspective views of coöperating portions of the clamping band and actuating means 45 for gripping the open end of the casing to hold the cover securely in place.

Referring to the drawings, the numeral 1 designates the casing of the door check and holder, which is provided internally 50 and intermediate of its ends with the interior screw threads 2 for the reception of the partitioning disk 3. The spindle 6 projects through the disk 3 and is keyed to the exteriorly screw threaded member 9 mounted for movement in the spiral groove 11 of

the plunger 12. A vertical slot 21 is formed in the circumferential wall of the plunger 12 and engages or fits upon the pin 22 carried in the casing 1, thus locking the plunger 12 against rotation so that as the stem 6 is oscillated, the member 9 will impart a vertical sliding movement to the plunger 12, the spring 21^a acting as a cushioning means for the plunger in its descent and also assisting in the ascent of the same. 60

The spring 26 is connected to operate the stem 6 through the sleeve 29, which is disposed for oscillation within the central opening 30 of the disk cover 31, said cover 31 being provided with the rim or flange 70 31^a which fits snugly within the upper end of the casing 1 and thus seals the same. By this means, the sleeve 29 may be independent of the spindle 6, and also the cover 31. Formed integral with the sleeve 29 is a disk 75 32 which is adapted to fit above the cover 31, the same being provided with a plurality of recesses 33 in its periphery. The reduced end 6' of the spindle 6 has detachably connected thereto by means of the 80 split clamping end 34, the inner arm 35. A lug 36 is formed integral with the arm 35 and has pivoted therein, a pawl 37, which is normally held by its spring 37' in engagement with the periphery of the disk 85 32 so as to, when the arm 35 is moved in the direction of the arrow Fig. 2, rotate the disk 32 and thus place the spring 26 under tension.

A lug 38 is formed integral with and projects from the periphery of the split clamping band 46 at one point thereof, and is disposed to coöperate with the abutment 39, which in the present instance carries the anti-frictional roller *a* so that when the 90 arm 35 is moved to a position to hold the door open, the roller will be positioned upon the opposite side of such lug 38 to that shown in Fig. 2, and the arm will thus be locked against movement. The pin 39 95 is carried by a block 41 disposed for sliding movement within the casing 42 formed in the arm 35 and covered by the plate 40. A spring 43 is disposed therein to normally hold the block 41 and the roller *a* toward 100 the periphery of the cover 31. By this means, when the roller *a* is forced in engagement with the lug 38, the same will roll thereabout and thus depress the spring 43 as the block 41 is moved outwardly, said 110

spring snapping the same in behind the lug 38 and thus locking the parts in the desired position with the door open.

The adjustable arm 44 is as usual pivoted 5 to the outer end of the arm 35.

A head or rim 45 forms a limiting means for the clamping band 46, that carries the lug 38, and said band has formed integral therewith, the two ears 47, recessed upon 10 their outer faces as at 48. These ears 47 are apertured for the reception of the clamping bolt 50, which binds the two arms or links 51, relatively to the ears 47, the arms 51 being provided with the rounded 15 projections 52 for registration with the recesses 48, and so that when said arms are pulled downwardly through the instrumentality of the bolt 53, the link 54, and the adjusting member 56, the ears 47 are forced 20 more closely together and the band 46 is clamped more firmly upon the casing. The member 56 is provided with the projection 55 to which the link 54 is secured, and has its socket 57 embracing the cylindrical boss 25 58 carried by the casing. A screw 59, having its head 60 accessible is mounted in the member 56 and limits the upward movement of the member 56 relatively to the boss 58. A spring 61 is provided and has its 30 terminals, which normally separate, connected to the ears 47 to assist in opening the band 46.

The lower end of the member 56, is in the form of a knob to permit the easy movement 35 downwardly of such member to more firmly clamp the band 46, after the door check and holder has been installed, the screw 59, being thus adjustable with a screw driver to hold the member 56 in such desired position.

What is claimed is:

1. A door check and holder, having a supporting casing, a split clamping band surrounding the upper end of said casing, 45 adjustable means pivoted to the band and connected to the lower end of the casing for

regulating the tension of the clamping band, a fluid cushioned and spring actuated means mounted in and exteriorly of the supporting casing, a folding arm connected to the latter means, and coöperable locking means for the folding arm carried by the band and the folding arm.

2. A door check and holder, having a supporting casing, a spring actuated folding 55 arm journaled in the supporting casing, a clamping band surrounding the upper end of the supporting casing, manually operated means for adjusting the band and locking it in clamped position, an arm holding lug 60 carried by the band, a resiliently mounted abutment carried by the folding arm for coaction with the lug of the band to lock the arm against the tension of its spring, said manually operated means including a 65 cam mechanism operably connected to the clamping band, a slidably operating member connected thereto and to the supporting casing, and means for locking said operating member in clamping position.

3. A door check and holder, having a main supporting casing provided with a stud at one end, a folding arm mounted upon the supporting casing for swinging movements, a spring for opposing the movement of the arm in one direction, a clamping band surrounding the supporting casing, coöperative means carried by the band and arm for limiting the movement of the arm in one direction, a pivoted wedging 80 member connected to the band, and an adjusting and operating member for the wedging member mounted upon the stud of the supporting casing.

In testimony that I claim the foregoing as 85 my own, I have hereto affixed my signature in the presence of two witnesses.

ALEXANDER RISPEL.
